PORTABLE CRANE

John E. Tom, Cleveland, Ohio

Application January 22, 1944, Serial No. 519,325

7 Claims. (Cl. 212—59)

This invention relates broadly to cranes and more specifically to cranes of the type that are designed for use and operation in conjunction with power driven vehicles.

One of the objects of the invention is to provide linkage associated with the boom to effect horizontal movements of the load beyond the center of gravity thereof in order to accommodate loading operations in such environs as require the projection of the load through a side wall opening or the deposit thereof upon a platform disposed beyond the vertical swing of the boom.

Another object of the invention is to provide a hoist mechanism on the chassis frame of the crane which is arranged for operation from the winch or power take-off on the vehicle.

Another object of the invention is to provide a platform on the boom of the crane to accommodate the support of workmen in contiguous relation with the suspended load in order to facilitate manipulation thereof or service attendant the procedure of installation and repair.

Another object of the invention is to construct a coupling between the crane and the vehicle with which it is associated so that only a fractional part of the weight of the crane will be borne by the vehicle and none of the load will be imposed upon the vehicular springs.

Another object of the invention is to provide a steering mechanism for the crane chassis which is operable independent of the vehicle steering gear.

Another object of the invention is to provide a boom which is adapted for adjustment in a substantially horizontal plane to facilitate negotiation of highway underpasses, towing of the assembly at relatively high rates of speed and storage of the crane within buildings of orthodox construction.

Another object of the invention is to provide mechanism for oscillating the boom in a horizontal plane about an axis normal to the chassis frame therefor.

Another object of the invention is to provide independently operable jacks for each of the wheels to facilitate adjustments of the chassis compensative with ground inclinations or irregularities.

Another object of the invention is to construct a crane having the component parts thereof free from cross members or large protrusions so that the crane, when dismantled, may be readily handled while in transit.

Another object of the invention is to provide

a connection between the crane and vehicle which will accommodate limited independent movement thereof.

Another object of the invention is to provide a readily detachable cable connection between the crane differential winch and the power driven winch on the vehicle.

Further objects of the invention reside in a crane which is designed to meet the requirements of deck and aircraft loading, a structure which is light and durable and a mechanism which is economic of manufacture and assembly.

Other objects and advantages more or less ancillary to the foregoing and the manner in which 15 all the various objects are realized will appear in the following description, which considered in connection with the accompanying drawings, sets forth the preferred embodiment of the invention.

20 In the drawings wherein preferred embodiments of the invention are illustrated:

Fig. 1 is a side elevational view of the improved crane including one of the types of vehicles that may be used therewith;

25 Fig. 2 is a front elevational view of the crane illustrated in Fig. 1;

Fig. 3 is a plan view of the crane showing, in dotted lines, the forward end of the boom lever in its lateral actuated positions; and

30 Fig. 4 is a plan view of a fragmentary portion of the crane deck plate and the swivel mechanism associated therewith.

Referring first to Fig. 1, the crane comprises a chassis frame 10 embodying side rails 11, an axle 12 of conventional automotive design, wheels 13 mounted thereon and cross members 14 uniting the side rails of the frame. The upper face of the frame is provided with a deck plate 15 fulcrumed upon a pin 16 mounted in the forward cross member 14. The rearward portion of the plate is provided with a mast 17 formed of uprights 18 connected at their upper ends with a gusset plate supporting a sheave 19 and a pair of links or stay bars 20. The boom 21 comprises

35 a pair of channel irons 22 secured at their lower ends to a cross rail 23 which is secured in turn to side braces 24 fulcrumed in brackets 25 mounted upon the forward end of the plate 15. The upper end of the boom is formed with a forwardly disposed extension 26 drilled for the reception of a pin 27 having a lever 28 and sheave 29 mounted thereon. The forward end of the lever is provided with a sheave 30 for the support of

40 the load carrying cable 31. The inner portion of the cable 31 is trained over the sheaves 29

45

50

55

and 32 and around a small drum 33a on a winch 33 mounted on the chassis frame. The winch 33 is further provided with a large drum 33b adapted to receive the free end of the cable 34 from the power winch 35 on the vehicle 36. In the event the power output of the vehicular winch or the running speed of the cable 31 is inadequate the diameter of the drum 33 may be increased relative to the diameter of the winch to produce the desired mechanical advantage.

The rearward end of the lever 28 is coupled with the stay bars or links 20 which are of a suitable length to maintain the forward end of the lever 28 in a substantially horizontal position when the boom is raised or lowered. Vertical adjustments of the boom are effected through a manually operable winch 38 mounted on the mast 15, the winch being provided with a cable 39 trained over the sheave 19 and anchored in a bracket mounted on the upper end of the boom.

The forward face of the boom is provided with a platform 40 to accommodate access to the load for the purpose of adjustment, such for example as required in the securement of a replacement engine in an airplane, the installation of a propeller, or the assembly of a structural element with the component part therefor. The platform is preferably hinged upon a carriage 42 supported upon rollers 43 which are guided in the channel irons 22. Vertical adjustment of the carriage may be effected by a chain fall 44 mounted on a shaft adjacent the top of the boom having spools 45 thereon coupled through cables 46 to the carriage 42. Cross bars or rungs 47 are secured to the rearward face of the channels 22 to form a ladder and a guard rail 48 is provided on the platform for the safety and convenience of the workmen. The platform is retained in a horizontal position, irrespective the inclination of the boom by adjustment of the chain 49.

The axle 12 is formed with steering knuckles, a drag link and a steering gear of conventional form coupled in the usual manner with a steering column 50 so that the crane assembly may be readily handled in transit and accurately "spotted" for the loading operation.

The chassis frame 10 is mounted upon jacks 51 pivotally connected with the axle 12 and held against lateral movement by a pintle 52 having a ball end thereon guided in a housing 53 in the center of the axle. The jacks may be of the hydraulic self contained type adapted for manual operation through the medium of a pump constituting a part of the unitary structure. The axle is further braced against lateral movement by the rods 54 mounted for vertical pivotal movement on both the axle and frame. The frame leveling mechanism embodied in the improved crane affords not only a means of shifting the center of gravity of the superstructure when it is necessary or convenient to use the crane on uneven ground but also affords a means of relieving the torsion on the side rails of the crane when the ground on one side of the vehicle is higher than that of the other.

As shown herein, the crane is coupled with a tractor through spherical ended pintles mounted on plates 55 bolted to the frame of the vehicle adjacent the center thereof and above the bogie or spring supported elements therein. It will be understood that other type of vehicles than the tractor illustrated herein may be employed in combination with the improved crane and that such combinations are contemplated as falling

within the scope and spirit of the present invention.

The rearward end of the deck plate 15 is retained against vertical movement by an angle iron 56 of arcuate form supported by brackets 57 mounted on the cross rail 14 and disposed to overlie the upper face of the rear edge of the plate. The lower face of the plate is provided with a lug 58 engaged with nuts or collars 59 mounted on a shaft 60 threaded in a bearing block 61 secured to one of the side rails 11. The outer end of the shaft 59 is formed with a hand crank 62 to facilitate rotation of the shaft and in turn oscillation of the plate, boom, mast and other mechanism mounted thereon. The rotational adjustment attained through the structure described above is intended primarily to facilitate lateral movements of the boom when it is desired to place the load with nicety upon a given spot and without alteration of the position of the vehicle.

In operation, after the crane is pushed or towed into proximity with the load, the boom is elevated to position, the lever 28 slightly above the floor level of the cargo carrier. The cable 31 is next affixed to the load sling and the vehicular winch 35 then operated through the clutch and control mechanisms 63 to effect the elevation of the load. The boom is next lowered through manipulation of the winch 38, the links 20 restraining movement of the rearward end of the lever 28 during this operation and effecting a substantially lineal movement of the load.

When the crane is moved any substantial distance the links 20 may be released, the platform collapsed, and the boom lowered to the position indicated by dotted lines in Fig. 1.

One of the utilities of the improved crane (but not the only one) resides in the use thereof in loading cargo airplanes, and/or elevating renewal elements therefor or removing heavy parts therefrom. In such environs the machine elements may be safely handled and accurately positioned with a minimum of labor and the motor mechanic on the platform 40 thus relieved of the hazardous task of shifting or lifting the load.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

I claim:

1. In combination with a tractor having a power operated winch thereon, a portable crane comprising a frame pivotally connected at one end thereof to said tractor, wheels on said frame adjacent the opposed end thereof, a boom pivoted upon said frame superjacent said wheels, a lever pivoted in the center thereof upon the free end of said boom, links pivotally connected with one end of said lever and with said frame, a load carrying cable coupled with the winch on said tractor and overrunning the opposed end of said lever, a winch on said frame, a cable operatively connected thereto and with said boom, parallel beams embodied in said boom, rollers engaged therewith, a platform carried by said rollers, and a cable supported by said boom and coupled with said platform to facilitate adjustments thereof.

2. In combination with a tractor having a power actuated winch thereon, a portable crane comprising a frame pivotally connected at one end thereof to the central portion of the tractor, an axle mounted upon the opposed end of said frame, wheels on said axle, a steering gear on said frame operatively connected with said wheels, hydraulic jacks intermediate said frame and said wheels, a pivotal connection between said frame and the central portion of said axle, a boom pivoted upon the forward end of said frame, a lever pivoted intermediate its ends to the free end of said boom, a mast on said frame rearward said boom, links pivotal thereto and with the inner end of said lever, a drum mounted on said mast, a sheave wheel mounted upon the opposed end of said lever, a cable trained thereover, and about said drum and the winch on said tractor, a second winch on said mast, a cable wound thereover and connected with the top of said boom and a platform mounted on the forward face of said boom and adapted for adjustment throughout the length thereof.

3. In combination with a motor vehicle having a power operated winch thereon, a crane comprising a frame, wheels mounted thereon adjacent the forward end thereof, means on said frame for steering said wheels, pivotal connections on said frame coupled with the vehicle at the center of gravity thereof, a boom pivoted upon said frame superjacent said wheels, a lever pivoted at its center upon the free end of said boom, means for raising and lowering said boom, links connecting one end of said lever with said frame rearward said wheel, a load carrying cable operatively supported upon the opposed end of said lever and connected with the winch on the vehicle, the length of said links and the portion of the lever connected thereto being proportioned relative to the length of the boom to delimit vertical movement of the end of said cable when the boom is lowered and to bias a portion of the load through the medium of the link upon the frame rearward the vehicle wheels.

4. In combination with a motor vehicle having a power operated winch thereon, a crane comprising a frame, wheels mounted thereon adjacent the forward end thereof, a steering gear on said frame operatively connected with said wheels, ball joint pivots on said frame coupled with the vehicle adjacent the center of gravity thereof, a boom pivoted upon said frame superjacent said wheels, mechanism associated with said boom for moving the load carried by said boom horizontally without substantial change in the elevation thereof, means for raising and lowering the load carried by said boom, means for rotating said boom and independently operable jacks adjacent

the wheels on said frame for tilting the boom laterally.

5. In combination with a crawler type tractor embodying a power operated winch, a portable crane comprising a frame, wheels on one end thereof, ball joint connections between the opposed end of the frame and said tractor intermediate the ends thereof, a plate pivotally mounted on said frame, a boom mounted thereon over said wheels, means for raising and lowering said boom, mechanism for horizontal translation of the load without material vertical movement thereof, a load carrying cable on said boom, a winch on said plate, a small drum on said winch having said cable wound thereon, a large drum on said winch and a second cable wound about said large drum and connected with the power operated winch on the tractor.

6. In combination with a motor vehicle embodying a steering mechanism and a power-operated winch, a crane comprising a frame, a boom mounted thereon, mechanism for rotating said boom, mechanism for raising and lowering said boom, mechanism for moving a load suspended on said boom forwardly without material change in the elevation thereof, a load lifting cable on said boom controlled by said winch, an axle on said frame subjacent said boom, a pair of road wheels thereon, mechanism on said frame for steering said wheels, independently operable jacks intermediate each wheel and the frame, universal couplings between said frame and the vehicle, whereby said crane may be pushed directionally towards a loading station, steered into loading position independent the vehicle steering mechanism, leveled for operative manipulation of the boom, rotated to position and the load elevated and projected through a cargo receiving opening in a carrier without further movement of the vehicle.

7. In combination with a motor vehicle embodying a steering mechanism, a crane comprising a frame, a boom thereon, mechanism thereon for moving a load carried thereby forwardly without material change in the elevation thereof, universal couplings supporting said frame forwardly of said vehicle, an axle on the forward portion of said frame below said boom, wheels on said axle, a steering gear on said frame for the control of said wheels, and means for tilting said frame relative to said axle, whereby said crane may be pushed by said vehicle in the direction of a loading station, independently steered into loading position, and the boom tilted to effect the discharge of the load while elevated without manipulation of the vehicle.

JOHN E. TOM.
